UNITED STATES PATENT OFFICE.

LOUIS S. FLATAU, OF DALLAS, TEXAS, ASSIGNOR TO C. S. ROBERTS, OF CHICAGO, ILLINOIS.

DESIGN FOR A POST.

SPECIFICATION forming part of Design No. 29,897, dated December 27, 1898.

Application filed November 16, 1898. Serial No. 696,650. Term of patent 14 years.

To all whom it may concern:

Be it known that I, LOUIS S. FLATAU, of Dallas, in the State of Texas, have invented and produced a new and original Design for Posts, of which the following is a description, referring to the accompanying drawings, forming a part of this specification.

Figure 1 is a side elevation of the post, viewed so that the wires on the near side of the post cover up those on the far side; and Fig. 2 is a side elevation of the same turned slightly, so that all the wires may be seen.

The leading or material feature of the design consists in the approximately hexagonally woven or meshed wire structure of tubu-

lar or cellular form, terminating at the base in the anchoring projections shown. The wires forming the meshes are interwoven, as shown, and form a completely-seamless structure symmetrical from all sides.

I desire to claim as new and to secure by Letters Patent of the United States—

The design for a tubular woven-wire post, as herein shown and described.

Signed this 1st day of October, 1898, at 25 Dallas, Texas.

LOUIS S. FLATAU.
